UNITED STATES PATENT OFFICE.

WILLIAM R. CUNNINGHAM, OF BUCYRUS, OHIO, ASSIGNOR TO THE AMERICAN CLAY MACHINERY CO., OF BUCYRUS, OHIO, A CORPORATION.

DRYING-CAR FOR CLAY PRODUCTS.

No. 857,270.

Specification of Letters Patent.

Patented June 18, 1907.

Application filed April 10, 1907. Serial No. 367,452.

To all whom it may concern:

Be it known that I, WILLIAM R. CUNNINGHAM, a citizen of the United States, residing at Bucyrus, in the county of Crawford and 5 State of Ohio, have invented new and useful Improvements in Drying-Cars for Clay Products, of which the following is a specification.

This invention relates to certain new and 10 useful improvements in cars or vehicles designed, especially, for hacking brick for drying purposes.

The device is in the nature of a push-car and, as usual, the brick are hacked on the 15 same and men push the loaded car into the drying tunnels and from thence into the kilns, when the bricks are removed and the empty car is returned to the brick machine for re-loading. These cars are very commonly 20 used in connection with the manufacture of clay products, such as bricks and tiles and they are used for transporting the product of the brick or tile machine to the kilns for drying and burning purposes.

25 The present invention relates more particularly to the manner of mounting the journal boxes of the main axles of the car whereby the superstructure is self-adjusting relative to the supporting axles, provision being 30 thereby made to allow the car to automatically accommodate itself to the uneven conditions of the track.

The invention consists of the parts and the 35 constructions, arrangements and combinations of parts which I will hereinafter describe and claim.

In the accompanying drawings forming part of this specification and in which similar reference numerals indicate like parts in the 40 several views, Figure 1 is a perspective view of a car or vehicle embodying my invention. Fig. 2 is a sectional view on the dotted line A—A of Fig. 3. Fig. 3 is a side elevation of one of the hangers and journal boxes, showing 45 the exterior cap of the box removed.

In the modern brick-yard establishments, railroad tracks usually run from the brick or tile machines to the drying-tunnels and kilns and to such other parts of the yard as may be 50 necessary or desirable. The tracks usually are made of light T-rails fixed to cross-ties

which are placed either two or three feet apart. As a rule the track is not well ballasted, if ballasted at all, consequently it is very common for the track to be uneven and to spring 55 considerably under the load of the weighted cars which are designed to travel thereover. These cars usually weigh about 500 pounds, and are made of light structural-steel in order to reduce the weight as low as possible to 60 carry the load. Such a car is shown in Fig. 1 and the material used in its construction is structural-iron just as it is received from the rolling-mill, cut to length and riveted together in the usual or any appropriate manner. The material of which the car is so 65 largely composed, varies somewhat in size, and often the parts are bent or twisted and this has its effect upon the proper or smooth running of the car. The present invention 70 relates to the bearings in which the axles of the car are mounted, and a means whereby these bearings are appropriately hung from fixed portions of the car structure, as I will now describe.

75 Referring to Figs. 2 and 3, the numeral 2 represents a structural steel-angle one of which forms each of the side rails of the car, as shown in Fig. 1, to which angle 2 is bolted, by bolts 4, 4', the vertically disposed hanger 80 3, said hanger being formed with an outstanding shoulder or ledge 5 upon which the lower edge of the steel angle 2 seats.

As shown in Fig. 3, the lower portion of the hanger 3 is forked or bifurcated as shown to 85 form the arms 6, 7, the lower ends of said arms being enlarged and bored to form bearings for the shaft or bolt 10. The fork of the hanger 3 is arched at the upper side and in the space thus formed, and straddled by the 90 arms 6, 7, is mounted the bearing 11 for the journal end of the axle 16 upon which the main bearing wheels of the vehicle are mounted.

In constructing the journal boxes 11, I 95 prefer to bore out the inside to form a smooth surface 12, and in the annular space formed between this surface and the outer surface of the axle 16, I arrange an annular series of rollers 13, thereby forming an anti-friction 100 bearing for the journal-end of the axle. On the inner side, the journal boxes 11 are closed

by means of the inturned flange 14, except that an opening 15 is left in this flange to admit the end of the axle 16, said flange and an appropriate cap piece 1 at the outer side of the journal box, serving to inclose the series of rollers and to prevent the rollers working out of the box but allowing said rollers to rotate freely on the said track surface 12, formed around the inner circumference of the journal-box, as the shaft or axle 16 revolves. On one edge and on the outer periphery of the journal-box 11 are formed ears 17 and 18 which are pierced with holes to admit the bolts 21 which pass therethrough and by appropriate nuts thereby hold the cap in position on the journal-box and close the outer end of said box and protect the journal-end of the shaft or axle 16. At the lower central portion, the journal box is formed with a long bearing or hub 23 which is shown of sufficient length to approximately fill the space between the inner sides of the arms 6 and 7 of the hanger 3, said hub 23 having a bore adapted to register with the bores formed in the arms of the forked hanger whereby a bolt 10 may be passed through the arms of the hanger and through the hub 23 to form a bearing by which the journal-box may oscillate in a direction transverse of the direction of travel of the car. This bolt or shaft 10 is secured by appropriate nuts on the outer ends as shown in Fig. 3. From this construction it will be observed that the journal boxes for the ends of the axles which carry the bearing wheels are mounted to oscillate in, and relative to, the hanger by which they are suspended from the fixed portions of the car structure, and that the said boxes are equalizing and adjust themselves to a level position without regard to the unevenness of the track upon which the car travels, and in this respect much better results are obtained than when the boxes are rigidly fixed for in this latter instance when the wheels of the car pass over the uneven track and the car springs under the load, the anti-friction rollers 13 have a tendency to move out of alignment with the axle, causing them to lock the axle and also causing the car to run hard. In my case the construction provides for an equalizing bearing that will always adjust itself to a level position, or in other words, maintain the rollers 13 in perfect alignment with the axle of the bearing wheels, thus causing the car to run smooth without regard to the unevenness of the track.

Having thus described my invention, what I claim as new and desire to secure by Letters Patent, is:—

1. In a vehicle, the combination with the body thereof, the axle and bearing wheels thereon, of a journal-box in which each end of the axle is turnable, a vertically-forked

hanger fixed to the vehicle body, and means for pivotally-mounting the under side of the journal-box in the lower part of the fork of said hanger to enable the box to automatically respond to irregularities in the road-bed and to adjust itself relative to the fixed hanger. 70

2. In a vehicle, the combination with the body thereof, the axle and bearing wheels thereof, of a vertically-forked hanger fixed to the vehicle body, and a journal-box having a hub on its lower side pivotally mounted in the lower part of the fork of the hanger and adapted to oscillate transverse thereof. 75

3. The combination of a fixedly-secured hanger having a centrally disposed opening in its lower portion, a bolt in the lower portion of the hanger and extending across the opening therein, and a journal-box within the opening of the hanger having a hub on its lower side receiving said bolt whereby the box may oscillate transversely of said bolt. 80

4. The combination of a fixedly-secured hanger having a bifurcated lower portion forming two arms, said arms having holes therein axially in line, a bolt fitting said holes and extending transversely across the opening therebetween, a journal-box mounted in the opening of the hanger and having a hub-portion on its under side, said hub-portion being contained between the arms formed by the bifurcation of the hanger and being pivotally mounted on said bolt, whereby it may oscillate transverse thereof. 95

5. The combination of a fixedly-secured hanger having a bifurcated lower portion forming two arms, said arms having holes therein axially in line, a bolt fitting said holes and extending transversely across the opening therebetween, a journal-box mounted in the opening of the hanger and having a hub-portion on its under side, said hub-portion being contained between the arms formed by the bifurcation of the hanger and being pivotally mounted on said bolt, whereby it may oscillate transverse thereof, said box having a removable cap-plate over its outer side and having an inturned flange on its inner side with an opening to receive an axle or shaft, and an annular series of rollers within the box and retained longitudinally in place by said cap-plate and inturned flange. 110

6. A vehicle of the character described having in combination a body with angle-irons extending along the sides thereof, hangers fixed to said angle-irons and having bifurcated lower portions, axles having bearing wheels upon which the body is supported, and journal-boxes mounted in the bifurcated portions of the hangers and receiving the ends of the axles, said boxes having roller-bearings and having lower portions pivotally hung within the bifurcated por- 115 120 125

tions of the hangers whereby the boxes oscillate relative to the hangers and in response to unevenness of the surface over which the vehicle travels, and the alinement of the roller-bearings with the axles is maintained.

5 In testimony whereof I have hereunto set

my hand in presence of two subscribing witnesses.

WILLIAM R. CUNNINGHAM.
